UNITED STATES PATENT OFFICE.

JOHN FRANKLIN WHITMAN, OF PHILADELPHIA, PENNSYLVANIA, ASSIGNOR
TO ISAAC A. SHEPPARD & CO., OF SAME PLACE.

DESIGN FOR A PORTABLE RANGE.

SPECIFICATION forming part of Design No. 25,583, dated June 2, 1896.

Application filed April 25, 1896. Serial No. 589,127. Term of patent 14 years.

To all whom it may concern:

Be it known that I, JOHN FRANKLIN WHITMAN, a citizen of the United States, residing in Philadelphia, Pennsylvania, have invented 5 a certain new and useful Design for a Portable Range, of which the following is a specification.

My design for a portable range is fully illustrated in the accompanying drawing, in which 10 the figure represents the range in perspective.

The main feature of the design is the foliated and ribbon scrollwork on the several parts of the range.

15 The oven-door A has a medallion in the center representing a "chef," and surrounding this medallion is a scroll, one end terminating at the upper hinge and the other terminating at the lower hinge. A branch of this scroll is extended within the large scroll 20 and encircles the medallion. The main and branch scrolls are foliated.

At each corner of the oven-door are foliated scrolls. The two at the hinge side of the door terminate at the hinges, while the 25 two at the opposite side of the door terminate at the handle. The hinges are ornamented by a series of ribs in keeping with the scroll. The edge of the door has an ornamental rib.

30 The fire-door B is in keeping with the oven-door and is made in two sections, each section having a ribbon-scroll and a foliated scroll. This fire-door has an ornamental border.

35 The ash-pit door C has two ribbon-scrolls commencing at the hinges, crossing each other at the center, and terminating at the handle, and on the door are foliated ornaments commencing where the ribbon-scrolls cross. Near the hinge side of the door is an independent scroll.

40 The warming-oven door D has two ribbon-scrolls in keeping with the ribbon-scrolls on the ash-pit door, the said scrolls crossing one another at the center and terminating in small scrolls near the handle. Extending 45 above and below the crossing-point are foliated scrolls, and extending toward the cross-

ing-point at each side are also foliated scrolls, represented as tied to the short ribbon-scrolls.

The boiler-casing E has two panels *e e'*. The panel *e* is made in three sections, each 50 having two ribbon-scrolls which cross each other, forming a rosette at the center, the other spaces of the scrolls being filled in with fan-like ornamentations. The panel *e'* is made up of two enlarged scrolls extending the 55 width of the panel and crossing each other, in keeping with the scrolls of the panel *e* and the ornamentation on the warming-oven door D, and in the center of this panel *e'* is a foliated star-shaped rosette, and in each side are floral 60 ornaments, represented as tied to ribbon-scrolls, the spaces being filled with fan-like scrolls, and the panel is bordered at each side. At the top of the boiler-casing is a border made up of quadrangular scroll-like sections. 65

The upper warming-oven F has two doors ornamented in keeping with the oven-door A, and in the center of each door is a foliated rosette.

I claim—

1. The design for a portable range as herein described and as shown in the accompanying drawing.

2. In a design for a portable range the oven-door as herein described and as shown in the 75 accompanying drawing.

3. In a design for a portable range the fire-door as herein described and as shown in the accompanying drawing.

4. In a design for a portable range the ash-pit door as herein described and as shown in the 80 accompanying drawing.

5. In a design for a portable range the warming-oven door as herein described and as shown in the 85 accompanying drawing.

In testimony whereof I have signed my name to this specification in the presence of two subscribing witnesses.

JOHN FRANKLIN WHITMAN.
